Patented Aug. 14, 1917.

UNITED STATES PATENT OFFICE.

GEORGE W. RENEAU, OF DE VIEW, ARKANSAS.

POST-BRACE.

1,237,097.

Specification of Letters Patent. Patented Aug. 14, 1917.

Application filed August 13, 1915. Serial No. 45,328.

To all whom it may concern:

Be it known that I, GEORGE W. RENEAU, a citizen of the United States, residing at De View, in the county of Woodruff and State of Arkansas, have invented certain new and useful Improvements in Post-Braces; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to braces for fence and other posts, and has for its object to provide a brace simple in construction and efficient in use, which can be readily applied and when necessary removed from one post 20 and applied to another, and which by adjustment of its parts makes it possible to draw and hold the post perpendicular.

To the accomplishment of the foregoing and such other objects as may hereinafter appear the invention consists in the features hereinafter particularly described and then sought to be clearly defined by the claims, reference being had to the accompanying drawing forming a part hereof, and in

30 which—

Figure 1 is a side view of the fence and post with the brace applied thereto;

Fig. 2 is a plan view of the same;

Fig. 3 a detail view of the lower part of 35 the brace with the loop or eye at the end of the tie-rod in section;

Fig. 4 is a perspective of a portion of a post and brace rod and bearing-plate for the upper end of the bar;

40 Fig. 5 a perspective of the bearing-plate; and

Fig. 6 a section through the same.

In the drawing the numeral 1 designates a post which may be of wood, metal, cement, or other suitable material, and of any desired shape in cross section. The numeral 2 designates a diagonally disposed brace bar which may be solid but preferably is tubular, and is formed with a knob or shoulder 3 50 near its lower end, the same preferably being cast with or otherwise formed as an integral part of the bar. The numeral 4 designates a tie-rod of suitable metal and formed at one end with an eye or loop 5 that encircles or grasps the diagonal brace bar near its lower end beneath the knob or shoulder 3

and abutting against the shoulder which prevents the tie-rod from slipping up on the diagonal bar when the tie-rod is tightened for drawing the post and tying it in a 60 perpendicular position. It will be observed that the lateral tie-rod and the diagonal brace constitute a brace one to the other at the point where the diagonal brace passes through the eye or loop of the tie-rod as one 65 bears against the other at such point and thus each tends to resist side thrust of the other at such point, as well as one constituting to some extent a support for the other. This affords additional strength and rigidity to the structure. One end of the tie-rod passes through the post and is threaded to receive a washer 6 and nut 7 by which the parts of the brace are drawn taut. The lower end of the diagonal bar is set into a 70 concrete base 8 and its upper end bears against the face of the post and sets into a recess formed either in the post as indicated in Fig. 1, or in a bearing plate 9 attached to the post as indicated in Fig. 4. If fitted 75 in a recess formed in the face of the post, a suitable staple 10 may be employed to secure the end of the bar in the post; or if the bearing plate 9 is used the end of the bar will fit in the recess 12 of the plate, and the 80 plate will be secured to the post by studs or prongs 13. In either case the end of the bar will be prevented from slipping sideways; and when the nut on the tie-rod is tightened the diagonal bar and post are held 85 rigidly and securely together and the post braced in a perpendicular position. The opposite ends of the diagonal bar are preferably beveled as illustrated so as to fit snugly to their respective bearing surfaces.

90 The construction and arrangement of parts are such that the possibility of the parts slipping or becoming loose is practically prevented and a strong and rigid brace for a post, whether for fencing or other purposes, 100 is provided, and in which the post may be drawn and rigidly braced in a perpendicular position most efficiently is provided for. If the post be of wood and it becomes necessary to replace it the brace can be readily detached from the old and applied to a new post. It is also of particular advantage for end or corner posts as the strength and stability of the bracing afforded makes one brace at such point sufficient and thus the 105 additional posts and additional braces often required at corners can be dispensed with.

I have illustrated and described some of the advantages of the construction, and have illustrated and described the preferred details of the several parts but changes can be made therein and essential features of the invention not departed from.

Having described my invention and set forth its merits what I claim is:

1. The post-brace comprising the diagonally extending brace-bar, and a laterally extending rigid tie-rod rigidly connected at one end to the post to be braced and at the opposite end formed with a rigid eye through which the diagonal brace passes and which engages said brace so as to afford a stiff, rigid connection between the brace and rigid tie-rod and support for the brace-rod.

2. The post-brace comprising the diagonally extending brace-bar provided near its lower end with a fixed abutment, and a laterally extending rigid tie-rod rigidly connected at one end to the post to be braced and at the opposite end formed with a rigid eye through which the diagonal brace passes, the fixed abutment of the brace and the rigid eye of the tie-rod interlocking with each other and affording a rigid support for the brace at the end of the tie-rod.

In testimony whereof I affix my signature in presence of two witnesses.

GEORGE W. RENEAU.

Witnesses:
